UNITED STATES PATENT OFFICE

VICTOR H. PALM, OF BUTLER, PENNSYLVANIA

INTERNAL COMBUSTION ENGINE

Application filed October 3, 1930. Serial No. 486,086.

My invention relates to internal combustion engines of the two cycle type, and more particularly to valve mechanism therefor.

One object of my invention is to provide a two cycle engine having power and pumping cylinders arranged in tandem, and improved valve mechanism for controlling the inlet passages of the associated power and pumping cylinders.

10 Another object of my invention is to provide a valve mechanism of unitary and simplified construction, and of novel arrangement of parts whereby only a single actuating member is necessary to actuate the same.

15 Further objects in the construction and operation of my invention will be apparent from the detailed description which follows, taken in conjunction with the accompanying drawings wherein.

20 Figure 1 is a side elevational view of a four-cylinder internal combustion engine embodying the principles of my invention; Fig. 2 is a view taken on the line II-II of Fig. 1, and Fig. 3 is a sectional view, on an enlarged scale, of a portion of the apparatus of Fig. 2.

25 Referring to Fig. 1 of the drawings, my invention involves the use of a plurality of power cylinders 4, 4a, 4b and 4c, each power cylinder being arranged in tandem with a pump cylinder 5, 5a, 5b and 5c, respectively. Although four pairs of associated power and pump cylinders are shown, a greater or less number of pairs may be employed, as desired.

30 As shown more clearly in Fig. 2, the pump cylinder 5 is mounted on a crankcase 6 in which a crankshaft 7 is journalled. The power cylinder 4 is provided with a cylinder head 8, an inlet port 9, an exhaust port 10, and a piston 11, the piston 11 controlling the port 10, in its reciprocating movement, to establish connection with the atmosphere through an exhaust passage 12. The cylinder head 8 and cylinder 4 are provided with usual water passages 13 through which cooling water circulates to prevent overheating of the parts. An intermediate head 14 is disposed between the cylinders 4 and 5, and is provided with a stuffing box 15 for packing a piston rod 16 that connects the power piston

11 with a piston 17 of the pump cylinder 5. A vent 18 is provided in the wall of the power cylinder between the underside of the piston 11 and the intermediate head 14 to provide for the flow of cooling air at the underside 55 of the power piston 11. The pump piston 17 is connected by a wrist pin 19a to a connecting rod 19 which is journaled on a crank 20 of the crank shaft 7, the various cranks 20 being disposed on the quarter relatively to 60 one another.

A cam shaft 21 is journalled in the crank case in parallel alignment with the crank shaft 7, and is rotated at the same speed as the crank shaft, through timing gears 22 65 and 23 which are shown more clearly in Fig. 1. The cam shaft 21 carries a series of cams 24 that are disposed in relative angular relation to each other in a manner well known in the art, in order to effect proper timing 70 of valve mechanism that is provided for controlling the inlet passage of each power cylinder.

In the ordinary form of two cycle engines, a valve mechanism is employed for controlling the inlet passages of the power cylinders, and a separate valve mechanism is used therewith to provide for the proper control of the ingress and egress of fluid to the pumping cylinders. In such a structure, a second series of cams is usually provided, or a duplicate cam shaft and cams are used, to actuate the valve mechanism of the pump cylinders. Still other forms of valve mechanism are used, such as gear driven rotary valves; in 75 any case, necessitating the use of duplicate parts or additional equipment to provide for the necessary control of fluid flow to and from the various associated cylinders. It is to be noted, however, that in accordance with 80 my invention, I provide only one cam for actuating and timing a valve mechanism for each power cylinder and its associated pump cylinder, as shown in Figs. 1 and 2, thereby 85 eliminating the duplicate parts and additional equipment ordinarily employed.

90 Referring more particularly to Fig. 3 of the drawings, the cylinderhead 8 of each power cylinder is provided with an extended portion 25 which is recessed as indicated 95 100

at 26, the inlet 9 having communication with the recess. A poppet valve 27 is supported within the recess 26 by a valve-supporting member 28 which is positioned in the recess, and retained therein by means of a casing 29 of the valve mechanism which is secured to the underside of the extended portion 25. The member 28 is provided with a valve seat to accommodate the disc of the valve 27.

10 The valve 27 is provided with a stem 30 that extends downwardly through a guide portion 31 of the member 28, and centrally of the casing 29. A valve spring 32 encircles the valve stem 30 and one end of the spring 15 abuts the lower end of the valve stem guide 31, and the other end engages a stop member or collar 33 which is rigidly carried by the valve stem, thereby to normally maintain the valve 27 in closed position. A spring-receiving cup 34 is interposed between the spring 32 and the guide portion 31, to retain the spring centrally of the valve stem.

15 A sleeve valve 35 is reciprocably positioned in the lower end of the valve casing 29, and 20 is provided with a vented passageway 35a in which the lower end of the valve stem 30 is 25 slidably supported. The valve 27 is actuated by movements of the sleeve valve 35; however, the valve 35 has a predetermined amount of free motion before engaging the 30 valve stem 30 to actuate the valve 27, for a purpose to be hereinafter described. A spring 38 is interposed between the collar 33 and the valve 35 to normally bias the same 35 toward open position, the spring 38, of course, being relatively weaker than the 40 spring 32.

45 The sleeve valve 35 is secured to one end of a push rod 36 that is provided with a cam roller or follower 37 at its lower end. The cam roller 37 engages the cam 24 and is actuated thereby to impart operating movement to the valves 35 and 27. The cam 24 is provided with a "raise" portion 24a which first engages the follower 37, thereby moving the valve 35 to closed position without moving the valve 27 to open position due to the lost-motion engagement between the valve 35 and the stem 30.

50 The cam 24 is provided with a "raise" portion 24b that engages the follower 37, following engagement thereof with the portion 24a, to impart further vertical movement to the valve 35, thereby moving the valve 27 to open position. This double movement of the valves 35 and 27 is necessary for a purpose to be hereinafter explained.

55 The sleeve valve 35 is provided with ports or passageways 40 that are brought into registry with ports 41 in the wall of the casing 29 when the valve is in the normal open position. The ports 41 communicate with the interior of a casing or manifold 42 which encircles the casing 29, and an opening 43 is provided in the casing 42 to establish com-

munication with the atmosphere there-through. However, by the use of the manifold 42 on each of the valve mechanism casings for each power cylinder, all the manifolds may be connected to a common pipe line 70 to which an air filter may be attached, or such pipe line may be connected to a suitable fuel supply or to a carbureting device.

75 The valve casing 29 is provided with an intake port 44 through which fluid under pressure from the pump cylinder which is associated therewith is conducted to the valve 27 that controls the passageway to its power cylinder. Each of the pump cylinders 5, 5a, 5b and 5c is provided with a port 45 to permit ingress and egress of fluid thereto for compression. The ports 44 leading to the valves 27 of the power cylinders 4, 4a, 4b and 4c are connected by conduits 46, 47, 48 and 49 to the ports 45 of the pump cylinders 5a, 5c, 5 and 5b, respectively, the pistons in the pump cylinders being 90° in the lead of the pistons in the power cylinders, in the order of connection named.

80 The heads 8 of the power cylinders are provided with fuel nozzles 50 which are provided with fuel lines 51 leading to a fuel injector pump 52 (Fig. 1). The pump 52 is actuated through suitable gearing 53 which is driven by the cam shaft 21.

85 The operation of the engine is as follows:—

90 During the power stroke of the pistons of the power cylinders 4, 4a, 4b and 4c, the valves 27 controlling the inlets thereof will be closed, while the sleeve valves 35 that are associated therewith will be in either open or close position, depending upon the position of the actuating cam 24 therefor. Since the power cylinders are connected to the charging or pump cylinders that are 90° in the lead thereof, respectively, the sleeve valves 35 that control the inlets of the pump cylinders are to be actuated 90° in the lead of the power valves 27 with which they are associated. Therefore, the actuating cams 24 for each valve mechanism are disposed on the cam shaft in angular relation of 90° with respect to each other. However, since the sleeve valves 35 are to be actuated 90° in the lead of the poppet valves 27, each cam 24 is disposed on the cam shaft in leading relation of 90° with the crank shaft, that is, with the "raise" 100 24a in advance of the crank 20.

105 Thus, as the pistons of the pump cylinders are 90° in advance of the pistons of the power cylinders with which they are associated and the cams 24 are disposed in leading relation of 90° with the crank shaft, the inlets of the pump cylinders will be closed by the action of the cams 24 moving the valves 35 to closed position at the end of the suction, or intake, stroke of the pump pistons at the time when the power pistons of the associated power cylinders are at one half of their power stroke.

110 Further, due to the lost motion operation

connection between the valve 35 and the valve 27, or the predetermined free movement of the valve 35 on the stem 30 of the valve 27, as hereinbefore described, the valve 35 is moved to closed position without effecting, or transmitting opening movement to the valve 27 of a power cylinder during the power stroke of its piston.

At the end of the power stroke of the power pistons, the intake valves 27 will be actuated by the engagement of the "raise" 24b of the cams 24 with the cam followers 37, whereby the valves 35 will be raised further to move the valves 27 to open position. Since the exhaust ports 10 of the power cylinders are uncovered by the power pistons at a predetermined point of the power strokes, the power cylinders are exhausted thereby; and, as the intake valve 27 of each power cylinder opens, air under pressure from the associated pump cylinder, the piston of which is at this time at the one-half point of its compression stroke, is admitted to scavenge the power cylinder so long as the exhaust port remains uncovered.

The dwell of the raise portion 24b of the cam 24 is such that the valves 27 remain open until the pistons of the pump cylinders reach the end of their compression strokes, the charge of which is being transferred through the connecting conduits to the associated power cylinders, thereby assuring a complete and fresh charge for the same; after which the cams permit the valves 27 and 35 to move to closed and open position, respectively, under the influence of the bias springs 32 and 38, such position being shown in Fig. 3.

Somewhat specifically, a cycle of movement of the engine is as follows:—

When the power cylinder piston 11 and the pump cylinder piston 17 are at their lower stroke, as shown in the drawings, the power cylinder 4 is exhausted by virtue of its piston uncovering the exhaust port 10 and scavenging air under pressure from the associated pump cylinder 5a, the piston of which is on its compression stroke, is delivered through conduit 46 and admitted past the valve 27 to scavenge the cylinder 4 so long as the exhaust port 10 remains uncovered. The valve 27 has been moved to open position by virtue of the raised portion 24b on the cam 24 engaging the cam follower 37, the cam 24 being in the position shown in Fig. 2 at the lower end of the power stroke. Also, a new charge of air has been drawn into the pump cylinder 5 through the port 45 and the conduit 48, such air charge being admitted to the conduit 48 through the opening 43, the registering ports 40 and 41 in the sleeve valve 35 and the valve casing 29, respectively, such valve and casing being associated with the power cylinder 4b, Fig. 1, and through the port 44 of said valve casing 29, as shown by the full line arrows in Fig. 3. The air charge in pump cylinder 5 is com-

pressed on the upstroke of its piston and delivered through conduit 48 to the valve casing 29, as shown by the dotted line arrows in Fig. 3, the sleeve valve 35 thereof having been moved to closed position by its actuating cam 24 upon the engagement of the raise portion 24a with the cam follower 37, immediately following the end of the power stroke of the piston 11.

As the piston of the power cylinder 4b is on its power stroke following the power stroke of the piston 11, the exhaust port of the power cylinder is uncovered and the cylinder scavenged in the same manner as described for the power cylinder 4, by the opening of its valve 27 under the influence of the raised portion 24b of its cam 24.

During the compression stroke of the power piston 11, the exhaust port 10 is covered and the compressed air charge from the pump cylinder 5a is continued to the power cylinder 4 through the conduit 46 and past the valve 27, until the piston of the pump cylinder 5a reaches the upper end of its compression stroke, at which time the cam follower 37 is released from the raised 24b of the cam 24, thereby to permit the valves 27 and 35 to close and open, respectively.

Fuel is injected into the power cylinders through the fuel nozzle 50 in timed relation to the compression stroke of the power cylinders, and the heat of compression of the air charge will fire the fuel charge. An induction ignition system of any well-known type that utilized an electric spark may be employed to fire the fuel charge, if desired.

With one revolution of the crank shaft, and with the cranks on the quarter, the firing order for each power cylinder will be 4, 4b, 4c and 4a, and the pump cylinders operate to scavenge and charge the power cylinders in the following sequence: cylinder 5 delivers its charge to the power cylinder 4b; 5b to 4c; 5c to 4a and 5a to 4.

It is evident from the foregoing description of this invention that two cycle internal combustion engines, formed in accordance herewith, may be scavenged and charged in a positive and efficient manner; and that a single cam arrangement may be employed to actuate a simplified double-acting valve structure of unitary form to accurately time the various phases in the operation of the engine.

I claim as my invention:—

1. The combination with a two cycle internal combustion engine having a plurality of pairs of power and pump cylinders arranged in tandem, superposed pistons in each pair of cylinders, and each power cylinder having a conduit connection with the pump cylinder the piston of which is in predetermined leading relation with the piston of the associated power cylinder, of a valve mechanism for controlling air charges for said associated power and pump cylinders through said con-

duit, a pair of interconnected valves in said mechanism, and means driven by the engine for actuating one of the valves of said mechanism in timed relation to the movement of the piston of the power cylinder and for actuating the other valve in timed relation to the movement of the piston of the associated pump cylinder.

2. The combination with a two cycle internal combustion engine having a plurality of pairs of power and pump cylinders arranged in tandem, superposed pistons in each pair of cylinders, a conduit connecting the power cylinder of one pair with a pump cylinder of another pair, the piston of which is in predetermined leading relation with the piston of the associated power cylinder, and a cam shaft, of a valve mechanism having a pair of valves for controlling the flow of air charges for said associated power and pump cylinders through said conduit, and a single cam on said cam shaft for successively actuating the said valves of the valve mechanism of each pair of cylinders in timed relation to the movement each of the pistons of the associated cylinders.

3. In an internal combustion engine, the combination with a plurality of pairs of power and pump cylinders arranged in tandem, superposed pistons in each pair of cylinders, a crankshaft and a cam shaft, of a valve mechanism therefor, comprising a valve casing, a valve controlled passageway between said casing and said power cylinder, a valve controlled passage between said casing and the atmosphere, a conduit communicating with the interior of said casing and having connection with the inlet port of the pump cylinder, the piston of which is in predetermined leading relation with the piston of the power cylinder, and means on said cam shaft having operative connection with said valves for successively operating the same in timed relation to the movement of the pistons of the associated power and pump cylinders.

4. In an internal combustion engine, the combination with a power cylinder and a pump cylinder, a piston in each cylinder, the piston of the power cylinder adapted for movement in a leading relation to the movement of the pump piston, of a valve mechanism therefor, comprising a valve casing having a port therein communicating with the atmosphere, a valve in the casing for controlling communication with the atmosphere, an air passageway in the power and pump cylinders, a conduit establishing communication between the air passage of the pump cylinder and the interior of the said casing, a second valve in the casing for controlling the inlet of the power cylinder, and having lost-motion operating connection with the first-named valve, and means operated by the engine, for successively actuating said valves

in timed relation with the movement of the pistons of the said cylinders.

5. In an internal combustion engine, the combination with a plurality of power cylinders, each having a pump cylinder associated therewith in leading relation to supply air under pressure, to scavenge and charge the same, and pistons in said cylinders of a valve mechanism for each pair of associated power and pump cylinders, comprising a valve casing, a poppet valve having a valve stem for controlling the inlet to the power cylinder, a conduit for effecting communication between the interior of the casing and the air cylinder, a second valve in the casing for controlling communication between the interior of the casing and the atmosphere, and a single cam rotatable in timed relation to the movement of the said pistons for actuating said valves, the said cam being operative to actuate the second-named valve in the lead of the actuation of the first-named valve.

6. A valve mechanism for internal combustion engines of the two cycle type having a power cylinder and an associated pump cylinder arranged to supply air under pressure to scavenge and charge the same, comprising a casing, a valve disposed at each end of the casing, a passageway leading to the inlet of the power cylinder and controlled by one of said valves, a passageway in communication with the atmosphere and controlled by the other valve, a conduit establishing communication between the pump cylinder and the interior of the casing, a lost-motion operating connection between said valves, and means for actuating said valves successively in predetermined timed relation.

7. A valve mechanism for internal combustion engines of the two cycle type having a power cylinder and an associated pump cylinder arranged to supply air under pressure to scavenge and charge the same, comprising a casing, a valve disposed at each end of the casing, a passageway leading to the inlet of the power cylinder and controlled by one of said valves, a passageway in communication with the atmosphere and controlled by the other valve, a conduit establishing communication between the pump cylinder and the interior of the casing, a lost-motion operating connection between said valves, and a single rotatable cam for actuating said valves successively in predetermined timed relation.

8. A valve mechanism for internal combustion engines of the two cycle type having a power cylinder and an associated pump cylinder arranged to supply air under pressure to scavenge and charge the same, comprising a casing, a valve disposed at each end of the casing, a passageway leading to the inlet of the power cylinder and controlled by one of said valves, a passageway in communication with the atmosphere and controlled by the other valve, a conduit establishing com-

munication between the pump cylinder and the interior of the casing, a lost-motion operating connection between said valves, and a rotatable cam having stepped raise portions on the periphery thereof and stepped in the direction of rotation for actuating the second-named valve and the first-named valve in the order mentioned in predetermined timed relation.

9. A valve mechanism for internal combustion engines of the two cycle type having a power cylinder, and an associated pump cylinder arranged to supply air under pressure to scavenge and charge the same, comprising a casing, a poppet valve having a valve stem disposed at one end of the casing and controlling a passageway leading to the inlet of the power cylinder, a sleeve valve in the other end of the casing and controlling a plurality of ports communicating with the atmosphere, a conduit establishing communication between the pump cylinder and the interior of the casing, the said sleeve valve having lost-motion operating engagement with the lower end of said valve stem, a spring normally maintaining said poppet valve in closed position, a relatively weaker spring positioned to urge the sleeve valve toward open position, and means operatively connected with said sleeve valve for initially actuating the same and for actuating said poppet valve through further movement of the said sleeve valve.

10. In an internal combustion engine, a power cylinder, a pump cylinder, a piston in each cylinder, the piston of the pump cylinder being operative in the lead of the power piston, a valve casing having a port therein connected to the inlet of the power cylinder, and a second port open to the atmosphere, a conduit communicating with the interior of said casing and having connection with the said pump cylinder, a valve member in said casing normally positioned to open communication through the said second port and to close communication through the other port during the suction stroke of the pump piston, means driven by the engine for initially actuating said member in timed relation to the movement of the pump piston, to close communication through the said second port, and means driven by the engine for effecting further actuation of said member in timed relation to the movement of the power piston, to open communication through the first-named port.

11. In an internal combustion engine, a power cylinder, a pump cylinder, a piston in each cylinder, the piston of the pump cylinder being operative in the lead of the power piston, a valve casing having a port therein connected to the inlet of the power cylinder, and a second port open to the atmosphere, a conduit communicating with the interior of said casing and having connection with the

said pump cylinder, a valve member in said casing normally positioned to open communication through the said second port and to close communication through the other port during the suction stroke of the pump piston, and a cam device driven by the engine for successively actuating said valve member in timed relation to the movement of the pump and power pistons, respectively, the said cam device having a rest portion, whereby the said valve member is maintained in normal position during the suction stroke of the pump piston.

In testimony whereof I, the said VICTOR H. PALM, have hereunto set my hand.

VICTOR H. PALM.
